UNITED STATES PATENT OFFICE.

ALFRED D. ANTOINE AND MYRON H. RICHARDSON, OF CHICAGO, AND ALBERT E. GEBERT, OF WILMETTE, ILLINOIS, ASSIGNORS TO ADVANCE MACHINE COMPANY, OF CHICAGO, ILLINOIS, A CORPORATION OF ILLINOIS.

PICTURE-EXHIBITING APPARATUS.

Application filed September 21, 1923. Serial No. 664,010.

To all whom it may concern:

Be it known that we, ALFRED D. ANTOINE, of Chicago, MYRON H. RICHARDSON, of Chicago, and ALBERT E. GEBERT, of Wilmette, all in the county of Cook and State of Illinois, and citizens of the United States, have invented certain new and useful Improvements in Picture-Exhibiting Apparatus, of which the following is a specification.

This invention relates to improvements in picture-exhibiting apparatus of the type in which a plurality of pictures or views, preferably of the stereoscopic type, are arranged within a casing and adapted to be successively brought into position to be viewed through windows or glasses, the shifting and changing of the views being controlled by mechanism adapted to be set into operation by the insertion of a proper check or token.

A further object is to provide an improved apparatus of this character including means whereby a predetermined number of views or pictures may be displayed during each period of operation of the apparatus.

A further object is to provide an improved apparatus of this character in which there is provided a rotatable view supporting member to which the views are pivotally connected, the views being successively brought into position to be viewed from a predetermined point, and improved means for imparting a quick or snapping movement to the views about their point of pivotal connection with the said support, as the views approach a predetermined point in the cycle of operation of the apparatus.

A further object is to provide an improved device of this character in which the view support may be readily disconnected from the actuating means therefor and removed with the views as a unit from the casing, without necessitating dismantling of the actuating mechanism or other parts of the apparatus, thereby rendering it possible to interchange the views and supports therefor as a unit.

To the attainment of these ends and the accomplishment of other new and useful objects as will appear, the invention consists in the features of novelty in substantially the construction, combination and ar-

rangement of the several parts, hereinafter more fully described and claimed and shown in the accompanying drawings illustrating this invention, and in which—

Figure 1 is a vertical sectional view of an apparatus of this character, and as taken on line 1—1, Figure 3.

Figure 2 is a vertical sectional view as taken on line 2—2, Figure 3.

Figure 3 is a horizontal sectional view as taken on line 3—3, Figure 2.

Figure 4 is a detail view taken on line 4—4, Figure 3.

Figure 5 is a plan view of one of the view carrying members.

Figure 6 is a side elevation of Figure 5.

Figure 7 is a sectional view as taken on line 7—7, Figure 3.

Figure 8 is a detail perspective view of a portion of the view carrying support and view carrying members.

Figure 9 is a detail perspective view of one of the escapement members of the motor or driving mechanism.

In this improved apparatus there is provided a view carrying drum like structure, embodying spaced members 10 and 11, which are held spaced from each other in any suitable manner, preferably by means of spacing devices 12. The drum thus formed is secured to a shaft 13 for rotation therewith, preferably by means of a fastening device 14, which passes through a suitable collar 15.

The drum is of any desired diameter and pivotally mounted between the members 10 and 11 thereof are view carrying members or supports 17, which latter are preferably constructed of sheet material of any desired configuration, one extremity 18 of which is bent back upon itself and spaced from the body portion of the member. The bent back portion 18 is preferably provided with a boss or projection 19, which is adapted to be embedded in a card 20, which carries the view, and when the latter is in position with respect to the member 17. This is accomplished by depressing or clamping down the turned back portion 18 of the members 17 and when thus clamped the card 20 will be held against accidental displacement with respect to the member 17. The other end of the member 17 is bent back upon itself as at 21 (see Figures 5 and 6) and the ex-

tremity thereof is preferably shaped to form a reduced finger 22, which co-operates with the portion 18 to hold the card 20 therebetween. A pivot pin 23 is clamped 5 between the members 17 and the turned back portion 21 and is secured to the member in any suitable manner, so as to prevent the pivot pin from rotating with respect to the member. Any suitable means may be provided for thus holding the pin and member 10 against relative movement. The ends of the pivot pin project beyond the ends of the turned back portion and one extremity of the pivot pin is deflected as at 24 to form 15 an arm. A shoulder 25 is formed on the member 17, adjacent the pivot pin, for a purpose to be set forth.

The members 17, any number of which 20 may be provided, are pivotally connected between the members 10 and 11 of the drum by passing the pivot pin 23 through registering apertures in the elements 10 and 11 and in such a manner that the arms or deflected extremities 24 of the pivot pins will 25 stand adjacent the outer face of the element 11. When the members 17 are thus connected with the drum it will be manifest that the members together with the cards 20 will be mounted for movement with the drum and with respect thereto. The shoulders 25 on the members 17 serve as a means for limiting the extent of movement of the members 17 about their pivots. Arranged 30 adjacent the outer face of the element 11 is a support 26, which is preferably pivotally mounted upon the axle or shaft 13 and has connected with it an arm 27, by means of which the support 26 may be moved about the shaft or axle 13, and which arm 35 also serves as a means for holding the support 26 against rotation with respect to the shaft or axle 13, in a manner to be herein-after set forth.

Pivots mounted upon the support 26 45 and adjacent the face of the element 11 is a member 28, preferably provided with an arm 29 having a portion 30, which is disposed adjacent the path of movement of the deflected portions 24 of the pivot pins 23 50 so that as the drum like structure or view carrying support is rotated, the portions 24 of the pivot pins 23 will successively engage the portion or surface 30 to rock the card carrying members 17 about their pivots 55 with respect to the drum like structure. Connected with the member 28 and also with the support 26, is a spring 31, which tends normally to move the member 28 in one direction about its pivot 32 and the member 60 28 is also provided with an arm 33, the extremity 34 of which is disposed in close proximity to the projecting portions of the pivot pins 23 and co-operated therewith to form a ratchet like construction, for the 65 purpose of holding the arm 29 and the sur-

face 30 of the member 28 against movement under the normal tendency of the spring 31. This extremity 34 of the arm 33 will, however, ratchet with respect to the projecting portions of the pins 23 as the 70 view carrying support is rotated in the direction of the arrow in Figure 2, which will, during the advancing movement of the view carrying support, cause the member 28, when the extremity 34 of the arm 33 is in engagement with one of the pivot pins, to move about its pivot 32 and against the stress of the spring 31. That is to say the member 28 will have a slight rocking movement about its pivot 32 as the view carrying support is advanced and until the extremity 75 34 of the arm 33 passes out of engagement with the respective pivot pin 23. At this point in the advancement of the view carrying support, the extremity 34 of the arm 80 33 will, under the influence of the stress created in the spring 31, slip or ratchet off of the respective pivot pin 23, allowing the spring 31 to exert its full force upon the support 28 to rock the latter in the opposite 85 direction. This will move the surface 30 of the arm 29 in the opposite direction about the pivot 32 with a sudden or quick movement. During this movement the surface 30 will engage the deflected portion 24 of 90 the next advancing pivot pin 23 and will impart a quick or sudden movement to the respective card carrier 17, thereby causing the view or picture to be thrown about its pivot quickly when it reaches a predetermined point in the operation of the apparatus, thereby insuring a proper changing of 95 the view and also without obstructing for any unnecessary period of time the next advancing view or picture. The extremity 34 of the arm 33 engaging the pivot pins also 100 serves as a means for holding the surface 30 in a proper position.

The parts thus constructed are arranged 110 within a housing or casing designated generally by the reference numeral 35 provided with windows 36-37 for admitting light into the casing and glasses 38, through which the pictures may be viewed.

The front of the casing is open and is 115 provided with a removable closure 39. Mounted upon one of the side walls of the casing is an open bearing 40 (see particularly Figures 3 and 4) and supported by the opposite wall of the casing is a rotatable bearing or socket 41 arranged in alignment with the bearing 40. The bearing 40 is 120 preferably spaced a slight distance from its supporting wall so that when the view carrying support and the shaft 13 are inserted into the casing through the open end thereof, one extremity of the shaft 13 may be inserted in the rotatable bearing or socket 41, after which the other extremity of the shaft 125 is placed within the bearing 40. As 130

a means for causing the shaft 13 to rotate with the bearing 41, the latter may be provided with openings 42, in which a lug or pin 43 carried by the shaft 13 is adapted 5 to be seated.

As a means for holding the shaft 13 against displacement with respect to the bearing 40, there may be provided a suitable locking device such as a bar or rod 44 (see 10 also Figure 3) adapted to slide in a suitable bearing 45 carried by the casing wall. The forward end of this bar or rod 44 terminates adjacent the open wall of the casing and the extremity is shaped to 15 form a handle 46, by means of which the bar or rod 44 may be moved in its bearing 45. The rear extremity 47 of the bar or rod 44 is deflected laterally and the deflected portion is adapted to move over the open 20 bearing 40 to lock the shaft in position in the bearing. When, however, it is desired to remove the view carrying support, the bar or rod 44 is moved inwardly or to 25 the left in Figure 3, until the deflected extremity 47 moves away from the bearing 40, thereby permitting the shaft to be raised out of the bearing and when thus raised may be shifted longitudinally so as to disconnect the other extremity of the shaft 30 from the rotatable bearing or socket 41.

Any suitable means may be provided for 35 rotating the bearing or socket 41, such as a spring motor device embodying a train of gears 48—49—50—51—52—53 (see particularly Figures 1 and 3) arranged within and mounted upon the side wall of the casing preferably upon a plate or support 54, (see Figure 1) secured in position by fastening devices 55, so as to permit the device to 40 be readily removed as a unit when desired. Connected with the gear 53 is a toothed escapement element 56, with which an escapement lever 57 co-operates. The latter is provided with trunnions 58 mounted in suitable 45 bearings and escapement teeth 59, which co-operate with the escapement element 56. Adjustably mounted on the element 57 are weights 60 for controlling the speed of oscillation of the element 57.

50 Rotatably mounted upon the bearing or socket 41 is a gear 61 and connected with the gear 61 for movement therewith is an arm 62. Carried by the arm 62 is a dog 63, which is movable therewith and with respect 55 thereto. This dog 63 is adapted to co-operate with a series of lugs or projections 64 extending laterally from the face of the gear 48. These lugs 64 are arranged at predetermined distances from each other, according 60 to the extent of movement or rotation which it is desired to impart to the bearing or socket 41 upon each step of operation of the apparatus. In the present form of the invention four of these lugs or projections are 65 shown, thereby insuring a one-quarter revolu-

tion of the socket 41 and gear 48 upon each operation of the device. The rotatable drum or view carrying support being connected with the bearing 41 for rotation therewith, it will be manifest that the view 70 carrying support will be given the same extent or degree of rotation upon each operation of the apparatus as is imparted to the bearing 41 and gear 48. This will insure the display of a predetermined number of views or cards 20 upon each operation. Obviously the number of pins or projections 75 64 may be increased or decreased according to the number of views desired to display upon each operation.

Connected with the arm 62 and with the dog 63 is a spring 65, which latter tends normally to move the dog 63 in a position to pass behind one of the pins or lugs 64, when the arm 62 is moved to the left in Figure 1. As this arm is moved in that direction the end or extremity 66 of the dog 63 will pass 80 behind the adjacent pin or lug 64, so that when the arm 62 is released and is moved in the opposite direction or toward the right in Figure 1, and the gear 61 rotated in a manner to be now described, the gear 48 and bearing 41 will be correspondingly rotated to rotate the view carrying support.

Any suitable means may be employed for 85 imparting such rotation to the gear 61. A suitable and efficient means embodies a rack 67 which meshes with the gear 61. This rack is connected with an arm or lever 68, pivotally supported intermediate its ends as 90 160 at 69 and upon the plate 54. The rack may be secured to the arm 68 in any suitable manner such as by means of a fastening device 70 passing through a flanged portion 71 of the rack. A spring 72 is anchored by one 95 extremity as at 73 to the arm 68 and by its other extremity as at 74 to a fixed support 75. The spring 72 is so arranged that its normal tendency is to move the rack 67 toward the left in Figure 1 so that the parts 100 will assume the position shown in full lines in Figure 1. To start the apparatus the extremity 76 of the arm or lever 68 is moved in a direction toward the left in Figure 1. As the rack 67 is connected with the arm 105 165 110 115 120 125 130 135 68, it will be manifest that such movement of the arm will advance the rack 67 by drawing the same forwardly or toward the right in Figure 1. This will rotate the gear 61 and as the arm or support 62 is connected with the gear 61 the arm will be swung toward the left in Figure 1, carrying with it the dog 63. When the arm 62 has been moved a sufficient distance to permit the end 66 of the dog 63 to drop behind one of the lugs or projections 64 on the pin 48 through the medium of the spring 65, the lever 68 may be released. During this movement of the lever 68 and before being released tension is being created upon the spring 72 to 140

store energy therein so that when the lever 68 is released the energy in the spring 72 will operate upon the lever 68 to move the latter in the opposite direction about its pivot and with it the rack 67. As the dog 63 is locked behind one of the pins or projections 64, it will be manifest that as the rack 67 is moved under the tension of the spring 72 to swing the arm 62 forwardly, the advancing movement of the arm 62 will rotate the gear 48. The arm 62 will continue to move under the influence of the rack 67 and gear 61 until the arm 62 engages a stop, which latter may, if desired, be the pivot 69 of the lever 68. When the parts assume the position shown in full lines in Figure 1, the arm 62 and gear 61 will be locked against further movement in that direction and at this time the operation of the apparatus will cease.

If desired a suitable guide roller 77 may be provided and over which the rack 67 moves, to hold the latter in mesh with the gear 61.

25 All of the propelling and the setting mechanism just described may be mounted upon the plate 54, so that the same may be removed as a unit or may be installed as a unit in the apparatus.

30 Any suitable means may be provided for swinging the lever 76 about its pivot against the stress of the spring 72. A suitable and efficient means embodies a crank arm 78, having a roller 79 connected therewith and which crank arm is connected with a shaft 80 for rotation therewith. A spring 81 is anchored to the shaft 80 by one end and by its other end as at 82 to a fixed support. The crank 78 may be rotated by means of a 40 suitable handle 83 arranged on the outside of the casing, while the crank 78 and spring 81 are arranged on the inside of the casing. When the crank 78 is rotated in an anti-clockwise direction the anti-friction roller 79 will engage the end 76 of the lever 68 and rock the same against the stress of the spring 72. This rotation of the crank 78 will create a tension upon the spring 81 so that when the handle 83 is released the 45 spring 81 will return the crank 78 to the position shown in Figure 1 and the lever 72 will be returned by the spring 72 and will be retarded in its movement through the medium of the gear 61 and rack 67.

50 The operation of the crank 78 may be controlled in any suitable manner but preferably through the medium of a check controlled mechanism diagrammatically illustrated at 84. This check controlled mechanism may be of the ordinary and well-known type and inasmuch as the same does not constitute a portion of the present invention, the details of construction and operation thereof have not been shown. Suffice 55 it to say, however, that when a proper check

or token is inserted in the check controlled mechanism, the handle 83 and crank arm 78 will be released to permit operation thereof.

It is thought that the operation of this apparatus will be clearly understood from the foregoing, but briefly stated it is as follows: The normal position of the parts are as shown in full lines in Figures 1 and 2. When a check is inserted in the check controlled mechanism the handle 83 and crank arm 78 are rotated to swing the lever 68 to the left in Figure 1 and also move the arm 62 with the dog 63 thereon to the left and into the position shown in dotted lines in Figure 1, until the end 68 of the dog 63 passes behind one of the lugs 64. The handle 83 is then released and the stress of the spring 72 will be exerted upon the lever 68 to return the latter. This return movement, however, is retarded by means of the escapement devices 57-56 and the train of gears 48-53. The gear 48 under the stress of the spring 72 will rotate in a clockwise direction and will continue to so rotate until the arm 62 engages the stop 69, at which time the motion of the parts will be arrested.

When the check is discharged from the check controlled mechanism it will pass through a suitable opening 85 into the enclosing housing or casing.

When it is desired, the front 39 of the casing is removed and the locking bar or rod 44 is moved inwardly so as to uncover the open bearing 40. The view carrying support may then be removed bodily as a unit by raising the end of the shaft 13, which rests in the bearing 40, a sufficient distance to permit the shaft 13 to be moved longitudinally so as to disengage the extremity thereof from the rotatable bearing 41, after which the views and the view carrying support may be bodily removed. The view carrying support may be replaced by reversing this operation.

The surface 30 on the arm 29 of the member 28 is adapted to be maintained in a proper position so as to trip or swing the card carriers 17 about their pivots to successively display the views as the support is rotated, so that they can be viewed through the glasses 38, by means of the arm 27, which is loosely mounted upon the shaft 13. This arm 27 is of a sufficient length to extend downwardly and terminate adjacent the bottom of the enclosing housing or casing and if desired an element 86, preferably in the form of a screw or bolt is threaded through a lateral projection 87 on the arm 27, so as to engage the bottom of the housing or casing. It will be manifest that inasmuch as the arm 27 is pivotally mounted upon the shaft 13 and inasmuch as it carries the element 28, any degree of movement of the arm 27 about its pivotal support

will shift the member 28 and consequently the surface 30. Therefore, by adjusting the screw or element 86 so as to vary the distance of the extremity of the arm 27 from the bottom of the casing, the position of the surface 30 may be varied to vary the time at which the deflected portions 24 of the pivots 23 will engage such surface.

It may happen when the reel or view carrying support is removed from the casing and re-inserted or a new one inserted therein, that the view support will not be in a proper position so that the operator will be able to see the proper views at the commencement of any one section of the views carried by the view support, and therefore the operation of the device under those conditions would result in the operator viewing a portion of the views in the two sections rather than all of the views in one section.

It is the purpose of this arm 27 and the adjustable element 86 to obviate this difficulty and that is accomplished in the following manner. The member 28 is so connected with the arm 27 that the surface 30 will always be maintained in the proper position with respect to the glasses 38, but in taking the reel and the arm 27 carried thereby out of the casing or inserting a new one therein, the reel may have been rotated with respect to the surface 30. Therefore, when the reel is placed back into the casing the arm 27 may be raised with respect to the reel or view carrying support, with the result that the free extremity thereof will project through the open face of and beyond the casing. It is immaterial what position this arm 27 assumes when the reel is being placed back into the casing. After the reel has been properly positioned and in order to adjust the reel with respect to the surface 30, all that is necessary is to insert a proper check into the mechanism and start the apparatus into operation. Under these conditions the arm 27 will travel with the reel or view carrying support until the extremity of the element 86 engages the bottom of the housing or casing, at which time the movement of the arm will be arrested, as will also the movement of the element 28 and surface 30. The reel or view carrying support will, however, continue to rotate until the arm 62 engages the stop 69, and this will happen just at the time that the end of any one particular section of views has been reached, thereby placing the first view or the descriptive card of the next section of views in a position to be viewed through the glasses 38.

It will be manifest that with this improved apparatus energy for each step of the operation thereof is created by the insertion of a check or token, or the setting of the apparatus for each particular operation

thereof. That is to say, when each check is inserted the setting of the apparatus as a result thereof, for operation, will store energy enough in the spring 72 so that in one particular operation this energy will be about expended, thereby rendering it unnecessary to maintain the spring 72 constantly under a considerable tension.

What is claimed as new is:—

1. An apparatus of the character described embodying a rotatable support, a plurality of view supporting members pivotally mounted upon the support, means for rotating the support, and means disposed adjacent the pivots of the said members for turning them about their pivots with respect to the support and at a predetermined point in the rotation of the support.

2. An apparatus of the character described embodying a rotatable support, a plurality of view supporting members pivotally mounted upon the support, means for rotating the support, means disposed adjacent the pivots of the said members for turning them about their pivots with respect to the support and at a predetermined point in the rotation of the support, and means for varying at will the point of operation of the last recited means.

3. An apparatus of the character described embodying a rotatable support, a plurality of view supporting members pivotally connected with the support, arms connected with the members adjacent their pivots, and means disposed within the path of movement of and adapted to engage the said arms when the latter are rotated with the support and operating to turn the said arms about their pivots and with respect to the said support.

4. An apparatus of the character described embodying a rotatable drum like structure, a plurality of view carrying members, means individual to the members and each embodying a pivot element for connecting the respective members with the support for movement therewith and with respect thereto, a portion of each of the said elements being shaped to form an arm, and a second element disposed within the path of movement of the said arms to successively engage the arms and turn the respective members about their pivots with respect to the said drum like structure.

5. An apparatus of the character described embodying a rotatable drum like structure, a plurality of view carrying members, means individual to the members and each embodying a pivot element for connecting the respective members with the support for movement therewith and with respect thereto, a portion of each of the said elements being shaped to form an arm, a second element disposed within the path of movement of said arms to successively engage the arms

and turn the respective members about their pivots with respect to the said drum like structure, and means whereby the point in the cycle of movement of the said arms at which the second recited element will engage the arms, may be varied at will.

6. An apparatus of the character described embodying a rotatable drum like structure, a plurality of view carrying members pivotally connected by one end with the drum like structure, one end of the pivot of each arm being extended and deflected to form an arm, an adjustable element, and a projection carried by said element and extending into the path of movement of the arms to be successively engaged by the arms for turning the said members about their pivots with respect to the said drum like structure.

7. An apparatus of the character described embodying a rotatable drum like structure, a plurality of view carrying members pivotally connected by one end with the drum like structure, one end of the pivot of each arm being extended and deflected to form an arm, an adjustable element, a projection carried by said element and extending into the path of movement of the arms to be successively engaged by the arms for turning the said members about their pivots with respect to the said drum like structure, and means for changing the position of the said projection to vary the point in the cycle of movement of the drum like structure at which the respective members will be moved about their pivots by the said projection.

8. An apparatus of the character described embodying a rotatable drum like structure, a plurality of view carrying members pivotally connected by one end with the drum like structure, a portion of the pivot of each member being shaped to form an arm, an element adjustable about the pivot of the said drum like structure, means for securing the said element in its adjusted position, and a projection carried by said element and extending into the path of movement of the said arms with the drum like structure and adapted to be successively engaged by said arms to rock the said members about their pivots.

9. An apparatus of the character described embodying a rotatable drum like structure, a plurality of view carrying member pivotally connected by one end with the drum like structure, one end of the pivot of each arm being extended and deflected to form an arm, an adjustable element, a projection carried by said element and extending into the path of movement of the arms to be successively engaged by the arms for turning the said members about their pivots with respect to the said drum like structure, and a shoulder carried by each of the said members and adapted to engage the periphery of the drum like structure for limiting the ex-

tent of pivotal movement of the member with respect to the drum like structure.

10. An apparatus of the character described embodying a rotatable drum like structure, a plurality of view carrying members pivotally connected by one end with the drum like structure, a portion of the pivot of each member being shaped to form an arm, an element adjustable about the pivot of the said drum like structure, means for securing the said element in its adjusted position, and a projection carried by said element and extending into the path of movement of the said arms with the drum like structure and adapted to be successively engaged by said arms to rock the said members about their pivots, a portion of each of the said members extending over and adapted to engage the periphery of the drum like structure for limiting the extent of pivotal movement of the members with respect to the drum like structure.

11. An apparatus of the character described embodying a movable support, a plurality of view supporting members pivotally mounted upon the support, means for moving the support, means disposed adjacent the pivots of the said members for turning them about their pivots with respect to the support and at a predetermined point in the movement of the support, and means for causing the movement of the view supporting members about their pivots with respect to the support to be sudden.

12. An apparatus of the character described embodying a movable support, a plurality of view supporting members pivotally mounted upon the support, means for moving the support, means disposed adjacent the pivots of the said members for turning them about their pivots with respect to the support and at a predetermined point in the movement of the support, and means influencing the second recited means for causing the latter to throw the said members about their pivots with a quick movement.

13. An apparatus of the character described embodying a movable support, a plurality of view carrying members pivotally connected with the said support, a projection connected with each of the members, and a resilient element, said element having a surface extending into the path of movement of the said projections for turning the said members with a quick movement about their pivots with respect to the said support.

14. An apparatus of the character described embodying a movable support, a plurality of view carrying members pivotally connected with the said support, a projection connected with each of the members, a resilient element, said element having a surface extending into the path of movement of the said projections for turning the said

members with a quick movement about their pivots with respect to the said support, and means for varying at will the point of operation of the said surface in the cycle of movement of the said support.

15. An apparatus of the character described embodying a movable support, a plurality of view carrying members pivotally connected with the support, a projection connected with each of the said members, a resilient element, said element having a surface to be engaged by the said projections for turning certain of the said members about their pivots with respect to the said support, and means whereby certain other of the said members will influence the said surface in its operation.

16. An apparatus of the character described embodying a movable support, a plurality of view carrying members pivotally connected with the support, an arm or projection connected with each of the members, a pivotally mounted element, said element having a formation adapted to engage the said arm or projection on said members for moving the latter about their pivots with respect to the said support, means tending normally to move said element in one direction about its pivot, and means whereby the movement of the said support will cause the said element to be temporarily moved in a direction about its pivot and against the stress of the first said means.

17. An apparatus of the character described embodying a movable support, a plurality of view carrying members pivotally connected with the support, an arm or projection connected with each of the members, a pivotally mounted element, said element having a formation adapted to engage the said arm or projection on said members for moving the latter about their pivots with respect to the said support, means tending normally to move said element in one direction about its pivot, means whereby the movement of the said support will cause the said element to be temporarily moved in a direction about its pivot and against the stress of the first said means, and means for also imparting a bodily adjustment to the said element and surface.

18. An apparatus of the character described embodying a movable support, a plurality of view carrying members pivotally connected with the support, an arm or projection connected with each of the members, a pivotally mounted element, said element having a formation adapted to engage the said arm or projection on said members for moving the latter about their pivots with respect to the said support, means tending normally to move said element in one direction about its pivot, and means operatively connected with the said element and the said view carrying members and coop-

erating to temporarily move the said member and surface about its pivot and against the stress of the first recited means.

19. An apparatus of the character described embodying a movable support, a plurality of view carrying members pivotally connected with the support, an arm or projection connected with each of the members, a pivotally mounted element, said element having a formation adapted to engage the said arm or projection on said members for moving the latter about their pivots with respect to the said support, means tending normally to move said element in one direction about its pivot, means operatively connected with the said element and the said view carrying members and co-operating to temporarily move the said member and surface above its pivot and against the stress of the first recited means, and means whereby a bodily adjustment may be given to the said element and surface.

20. An apparatus of the character described embodying a movable support, a plurality of view carrying members pivotally connected with the support, a portion of the pivot of each member being deflected to form an arm, a movable element, a surface carried by the element and extending into the path of movement of the said arms to be successively engaged thereby for turning the members about their pivots with respect to the said support, means tending normally to move the said element and surface in one direction, and means connected with the said element and co-operating with portions of other of the view carrying members for moving the said element and surface against the stress of the last recited means.

21. An apparatus of the character described embodying a movable support, a plurality of view carrying members pivotally connected with the support, a portion of the pivot of each member being deflected to form an arm, a movable element, a surface carried by the element and extending into the path of movement of the said arms to be successively engaged thereby for turning the members about their pivots with respect to the said support, means tending normally to move the said element and surface in one direction, and means connected with the said element and ratcheting with the pivots of others of said view carrying members for temporarily moving the said element against the stress of the last recited means.

22. An apparatus of the character described embodying a movable support, a plurality of view carrying members pivotally connected with the support, a portion of the pivot of each member being deflected to form an arm, a movable element, a surface carried by the element and extending into the path of movement of the said arms to be successively engaged thereby for turning the

- members about their pivots with respect to the said support, means tending normally to move the said element and surface in one direction, means connected with the said element and cooperating with portions of other of the view carrying members for moving the said element and surface against the stress of the last recited means, and an arm connected with the said element for bodily shifting the said element, said arm operating to maintain the said surface in a predetermined operative position with respect to the first recited arm.
23. An apparatus of the character described embodying a rotatable drum like structure, and a plurality of view carrying members pivotally connected at one end to the drum like structure, said members being formed from a single piece of sheet material, the ends of the arms being bent back upon themselves, the extremities being spaced from the body of the member to receive therebeneath the edges of a view carrying card, and a pivot pin secured within the fold at one end of the member, the turned back portion at the free end of the member being adapted to be clamped down upon the card to secure the latter against displacement with respect to the members.
30. 24. An apparatus of the character described embodying a rotatable drum like structure, a plurality of view carrying members pivotally connected at one end to the drum like structure, said members being formed from a single piece of sheet material, the ends of the arms being bent back upon themselves, the extremities being spaced from the body of the member to receive therebeneath the edges of a view carrying card, and a pivot pin secured within the fold at one end of the member, the turned back portion at the free end of the member being provided with an inwardly extending boss or projection adapted to be embedded in the surface of the said card for holding the latter against displacement with respect to the said member.
25. An apparatus of the character described embodying a rotatable drum like structure, a plurality of view carrying members pivotally connected at one end to the drum like structure, said members being formed from a single piece of sheet material, the ends of the arms being bent back upon themselves, the extremities being spaced from the body of the member to receive therebeneath the edges of a view carrying card, and a pivot pin secured within the fold at one end of the member, the turned back portion at the free end of the member being provided with an inwardly extending boss or projection adapted to be embedded in the surface of the said card for holding the latter against displacement with respect to the said member, a portion of the member ad-

jacent but spaced from the pivot in a direction lengthwise of the member being shaped to form a laterally projecting shoulder movable into and out of engagement with the periphery of the said drum like structure. 70

26. An apparatus of the character described embodying a rotatable support, a plurality of picture carriers mounted upon the support, means for rotating the support to position the pictures with respect to a view point, the said means embodying a motor including an escapement mechanism, a shiftable member for storing energy in the said motor to operate the latter, and means independent of the escapement mechanism 80 and operating to stop the motor at a predetermined point in the cycle of operation of the rotatable support.

27. An apparatus of the character described embodying a rotatable support, a plurality of picture carriers mounted upon the support, means for rotating the support to position the pictures with respect to a view point, the said means embodying a motor including an escapement mechanism, a shiftable member for storing energy in the said motor to operate the latter, means for shifting said member, and means independent of the escapement mechanism and operating to stop the motor at a predetermined 95 point in the cycle of operation of the rotatable support.

28. An apparatus of the character described embodying a rotatable support, a plurality of picture carriers mounted upon the support, means for rotating the support to position the pictures with respect to a view point, the said means embodying a motor including an escapement mechanism, a shiftable member for storing energy in the said motor to operate the latter, means controlled by the insertion of a check or token for shifting the said member, and means independent of the escapement mechanism and operating to stop the motor at a predetermined point in the cycle of operation of the 100 rotatable support.

29. An apparatus of the character described embodying a rotatable support, a plurality of picture carriers mounted upon the support, means for rotating the support to position the pictures with respect to a view point, the said means embodying a motor including an escapement mechanism, a shiftable member for storing energy in the said motor to operate the latter, means independent of the escapement mechanism and operating to stop the motor at a predetermined point in the cycle of operation of the 110 rotatable support, and means for imparting 115 a degree of movement to the said member sufficient to create substantially only enough energy in the motor to impart only a predetermined degree of rotation to the said rotatable support. 120

30. An apparatus of the character described embodying a rotatable support, a plurality of picture carriers mounted upon the support, means for rotating the support 5 to position the pictures with respect to a view point, the said means embodying a motor including an escapement mechanism, a shiftable member for storing energy in the said motor to operate the latter, means 10 independent of the escapement mechanism and operating to stop the motor at a predetermined point in the cycle of operation of the rotatable support, all of said parts being disposed within a closed casing, and 15 means accessible from the exterior of the casing for actuating the said movable member.

31. An apparatus of the character described embodying a rotatable support, 20 means for rotating the support, said means embodying a gear, escapement mechanism for controlling the rotation of the gear, an additional gear, a rack meshing with said additional gear, means tending normally to 25 move the rack in one direction, and means for moving the rack in the opposite direction and against the stress of the last recited means.

32. An apparatus of the character described embodying a rotatable support, 30 means for rotating the support, said means embodying a gear, escapement mechanism for controlling the rotation of the gear, an additional gear, a rack meshing with said 35 additional gear, means tending normally to move the rack in one direction, means for moving the rack in the opposite direction and against the stress of the last recited means, and a stop device independent of the 40 escapement mechanism and connected with the said additional gear for arresting the operation of the parts.

33. An apparatus of the character described embodying a rotatable support, 45 means for rotating the support, said means embodying a gear, a spring, an additional gear, a rack meshing with the said additional gear for rotating the latter forwardly and backwardly, means responsive in its 50 operation to the movement of the said additional gear and adapted to be set to rotate the first said gear, a lever connected with

the rack, said spring being connected with the lever to move it in one direction, means for shifting the lever to store energy in the 55 said spring, and means for retarding the rotation of the said gears under the influence of the said spring.

34. An apparatus of the character described embodying a rotatable support, 60 means for rotating the support, said means embodying a gear, a spring, an additional gear, a rack meshing with the said additional gear for rotating the latter forwardly and backwardly, means responsive in its 65 operation to the movement of the said additional gear and adapted to be set to rotate the first said gear, a lever connected with the rack, said spring being connected with the lever to move it in one direction, means for shifting the lever to store energy in the 70 said spring, and an escapement mechanism for retarding the rotation of the said gears under the influence of the said spring.

35. An apparatus of the character described embodying an enclosing housing, a rotatable drum like structure therein, view carrying members connected with the drum, means for inspecting the views from the outside of the casing and as the drum is rotated, and operating mechanism within the casing for rotating the drum, the said drum and view carriers being adapted to be disconnected from the said operating mechanism, and removed as a unit from the 80 housing.

36. An apparatus of the character described embodying an enclosing housing, a rotatable drum like structure therein, bearings for the drum, one of said bearings having a lateral opening through the wall thereof to permit the insertion and removal of one end of the drum shaft, the other bearing being rotatable, means co-operating with the said opening in the said bearing for locking the shaft against removal, and means for rotating the said rotatable bearing.

In testimony whereof we have signed our names to this specification, on this 15th day of September, A. D. 1923.

ALFRED D. ANTOINE.
MYRON H. RICHARDSON.
ALBERT E. GEBERT.
